ARMAND J. VALLEE, OF ALBANY, NEW YORK, ASSIGNOR TO SIGNAL ACCESSORIES CORPORATION, OF UTICA, NEW YORK, A CORPORATION OF NEW YORK

SOLDERLESS RAIL TERMINAL

Application filed June 16, 1930. Serial No. 461,523.

This invention relates to a device for connecting electric conductors and analogous objects to railway rails and is commonly known as a "rail terminal" for establishing an electric connection between the conductor and rail or may be used for securing the ends of bond wires to the adjacent ends of aligned rail sections.

The terminal ends of these conductors, whether made of single or stranded wires, must be rigidly secured to the rails to form the desired electrical connection therewith while the remaining portions are more or less free to vibrate, due to the passage of the rolling stock along the rails and frequently results in crystallization and consequent disintegration of the conductor adjacent its fixed connection with the rail.

The main object of the present invention is to provide simple and efficient means for reducing to a minimum this liability to disintegration and at the same time to protect the connection against excessive corrosion by climatic elements.

One of the specific objects is to provide one of the clamping members for the conductor with a more or less resilient outrigging arm adapted to embrace the conductor some distance from its point of rigid securing to the rail for reducing the vibration of the conductor and incidentally reducing to a minimum the liability of disintegration by crystallization.

Another specific object is to provide the other member with a marginal flange extending across the intervening space between the clamping members and around the adjacent portion of the conductor for protecting the latter and its retaining means against corrosion and also for holding the conductor loop on the post against opening.

Other objects and uses relating to specific parts of the device will be brought out in the following description.

In the drawing:

Figure 1 is a perspective view, partly in section, of a railway rail and portion of a conductor with my improved connecting device in operative position.

Figure 2 is an enlarged sectional view taken along line 2-2, Figure 1.

Figure 3 is an enlarged longitudinal sectional view taken along line 3-3, Figure 1.

Figure 4 is a longitudinal sectional view taken in the plane of line 4-4, Figure 3.

Figures 5 and 6 are perspective views, respectively on a reduced scale, of the clamping members for direct engagement with the conductor, the wings of the clamping member seen in Figure 5 being shown in their open positions to receive the conductor while in Figure 4 the same wings are shown as closed upon the conductor.

In order that the invention may be clearly understood I have shown a portion of a railway rail —A— having its web —a— provided with a transverse opening —a'— for receiving a tapered stud or bolt —1— of copper or other electric conducting material which is driven or otherwise tightly fitted in the opening —a'— to assure a perfect electric connection between the stud and rail.

The smaller end of the stud —1— is threaded at —2— and is of sufficient length to extend some distance beyond the adjacent portion of the rail when the stud is adjusted for use.

A nut —3— is engaged with the threaded extension —2— and adjacent portion of the web —a— so that when turned in one direction it may serve to tighten and hold the stud —1— in the opening —a'—.

A pair of apertured clamping members —5— and —6— are placed over and upon the threaded portion —2— of the stud —1— to embrace said stud between the nut —3— and an additional nut —7—, the portions of the clamping members —5— and —6— which embrace the threaded portion —2— of the stud —1— being arranged in spaced relation for receiving a portion of an electric conductor —8—. The portion of the clamping member —5— which embraces the stud —1— is substantially circular and is provided with a central opening —5'— for receiving the threaded portion of the stud.

This clamping member —5— is also provided with a radially extending arm —9—

projecting some distance from the stud —1— and having its distal end provided with a pair of opposed wings —10— projecting laterally therefrom in the same direction and 5 normally spaced apart transversely a distance sufficient to receive the adjacent portion of the cable —8— when adjusted for use.

The other clamping member —6— is provided with a substantially flat circular base 10 —11— having a central opening —11— adapted to receive the threaded extension —2— of the stud —1—, said clamping member —6— being provided with a marginal flange —12— projecting across the intervening space between said clamping members and adapted to embrace the circular inner end of the clamping member —5— and the adjacent portion of the conductor —8—, the 15 flange —12— having one side open at —13— to permit the passage of the conductor —8— therethrough.

The terminal end of the conductor —8— is preferably bared of its insulation —8'— 20 and bent into the form of a loop or eye adapted to embrace the threaded extension —2— of the stud —1— between the flat parallel portions of the clamping members —5— and —6— and within the marginal flange —12— of the clamping member —6— 25 as shown more clearly in Figures 2, 3, and 4.

When assembling the parts of the terminal connection the stud —1— per se is 30 first inserted tightly within the opening —a— and is then engaged by the nut —3— which is screwed against the adjacent portion of the web —a— for additionally tightening and holding the stud in the opening.

40 The clamping member —5— is then placed over and upon the threaded portion of the stud —1— and against the outer end face of the nut —3— after which the looped end —8''— of the conductor —8— is placed over 45 and upon the threaded portion of the stud —1— and against the outer face of the clamping member —5— so that the arm —9— will project radially from the stud along the conductor which will then be interposed between the wings —10—.

50 The other clamping member —6— is then placed over and upon the threaded portion of the stud —1— with its base —11— in engagement with the outer end face of the conductor eye —8''— under which conditions the opening —13— in the flange —12— will be registered with the adjacent portion of the cable and also with the adjacent portion 55 of the arm —9—, so that the flange —12— may embrace not only the eye —8''— but also the adjacent portion of the arm —9— of the clamping member —5—.

60 The circumferential width of the opening —13— is approximately equal to the width 65 of the adjacent portion of the arm —9—

so that the walls of the opening may engage opposite edges of the arm to hold the member —6— against turning when tightening the clamping nut —7—, it being understood, however, that the inner ends of the clamping members —5— and —6— including the flange —12—, constitute a housing for the adjacent portion of the conductor —8— to protect the same against undue corrosion by 70 climatic elements.

When the clamping members —5— and —6— and interposed portion of the conductor —8— are placed in operative position upon the stud —1— the nut —7— may be tightened to effect a corresponding firm tightening of the clamping members —5— and —6— and conductor eyes —8''—, one against the other to form a rigid connection with the stud and therethrough with the rail —A—, the clamping nut —7— being held in its tightened position by a lock nut —7'— of any suitable construction.

At any time after the clamping member —5— and conductor —8— have been assembled upon the stud —1— the wings —10— may be bent toward each other upon the adjacent insulated portion of the conductor —8— to relieve the free portions of the conductor from excessive vibration which, in that case, will be transferred to the arm —9—, thereby greatly reducing the liability of disintegration by crystallization of the portion of the conductor adjacent the stud —1—.

It is, of course, evident that when the nuts —7— and —7'— are loosened the arm —9— of the clamping member —5—, together with the adjacent portion of the conductor, may be turned to different angles about the axis of the stud as may be required for properly positioning the conductor relatively to the stud after which the nuts —7— and —7'— may be retightened to firmly hold the clamping members at adjacent portion of the conductor in operative position.

What I claim is:

The combination with a rail having a bolt-opening therethrough, a bolt passed through said opening and extended beyond opposite faces of the rail, said bolt having one end threaded and its opposite end tapered toward the threaded end and relatively larger than the opening, a nut engaging the threaded end of the bolt and adjacent face of the rail for drawing the tapered end tightly into the opening, a clamping member having one end embracing the threaded end of the bolt and engaging the outer end face of said nut and its other end provided with means for embracing an electric conductor, an electric conductor having an eye embracing the threaded end of the bolt and outer face of the adjacent portion of said clamping member, a cup-shaped clamping member having a flat bottom portion embracing the 115 120 125 130

threaded portion of the bolt and engaging the outer face of the conductor, said cup-shaped clamping member having its rim extended around the adjacent portions of the conductor and the first named clamping member and formed with an opening through which the adjacent end of the first named clamping member extends, and a nut engaging the threaded end of the bolt and outer end face of the second clamping member.

In witness whereof I have hereunto set my hand this 9th day of June 1930.

ARMAND J. VALLÉE.
